(57) **CLAIM**

We claim the ornamental design for a mouse trap, as shown and described.

DESCRIPTION

FIG. 1 is a front perspective view of a mouse trap according to the invention;

FIG. 2 is a rear perspective of FIG. 1;

FIG. 3 is a top plan view of FIG. 1;

FIG. 4 is a bottom plan view of FIG. 1;

FIG. 5 is a front elevational view of FIG. 1;

FIG. 6 is a rear elevational view of FIG. 1;

FIG. 7 is a left side elevational view of FIG. 1;

FIG. 8 is a right side elevational view of FIG. 1;

FIG. 9 is a front perspective view of a second embodiment of a mouse trap;

FIG. 10 is a rear perspective view of FIG. 9;

FIG. 11 is a top plan view of FIG. 9;

FIG. 12 is a bottom plan view of FIG. 9;

FIG. 13 is a front elevational view of FIG. 9;

FIG. 14 is a rear elevational view of FIG. 9;

FIG. 15 is a left side elevational view of FIG. 9; and,

FIG. 16 is a right side elevational view of FIG. 9.

The broken lines in the drawings illustrate portions of a mouse trap that form no part of the claimed design.
